UNITED STATES PATENT OFFICE.

SAMUEL F. PRIEM, OF SHAWANO, WISCONSIN.

HAT HOLDER.

Application filed September 27, 1922. Serial No. 590,930.

To all whom it may concern:

Be it known that I, SAMUEL F. PRIEM, a citizen of the United States, residing at Shawano, in the county of Shawano and State of Wisconsin, have invented certain new and useful Improvements in a Hat Holder, of which the following is a specification.

The present invention relates to a hat holder and has for its principal object to provide means whereby a hat may be readily supported on the back of a chair, church pew or in any other suitable place.

Another important object of the invention is to generally improve upon devices of this nature by providing a holder which will be extremely simple and efficient in construction, reliable in operation, comparatively inexpensive to manufacture, durable, and well adapted to the purpose for which it is designed.

With the above and numerous other objects in view as will appear as the description progresses, the invention resides in certain novel features of construction, and the combination and arrangement of parts as will be hereinafter more fully described and claimed.

In the drawing:—

Figure 1 is a front elevation of the hat holder embodying my invention, and

Figure 2 is a vertical longitudinal section taken therethrough.

Referring to the drawing in detail it will be seen that 1 designates the fixed member which is formed from a single sheet of material having its upper end bent over upon its body as at 2 and this overhanging portion is provided with a notch 3 in its edge. This fixed member is reduced intermediate its ends forming a lower portion 4 and an upper portion 5. Suitable fastening means 6 penetrate the upper portion 5 and similar means 7 penetrate the end of the lower portion 4. On the lower portion 4 adjacent the upper portion 5 there are situated a pair of ears 9 which are apertured and bent at right angles to the plate.

A movable or fulcrumed plate 10 is formed with a pair of angularly extending ears 11 which are also pierced so that a pin 12 may be passed therethrough and also through the ears 9. The lower end of the fulcrum plate 10 is curved toward the fixed plate 1 as at 13. A coil spring 14 is disposed about the pin 12 and provided with a

finger 15 adapted to bear against the upper portion 5 of the plate 1 and at its other end with another finger 16 adapted to bear against the upper portion of the plate 10, thereby holding the curved portion 17 normally in engagement with the lower portion 4 of the plate 1. This lower portion 4 of the plate 1 is provided with a curved or raised projection 18 situated so as to be situated immediately above the end of the curved portion 13 of the plate 10. The dotted line structure 18 represents the portion of the hat and shows how the same would be supported by the hat holder.

The overhanging portion of the fixed member partially encases the upper end of the movable or fulcrumed plate 10 thereby protecting the same and likewise preventing objects from coming into contact therewith such as articles of clothing which might become torn by the upper end of the fulcrumed plate and the notch 3 is provided therein so that ready access may be had to the upper end of the fulcrum plate for operation thereof.

It is thought that the construction and operation of the invention will now be readily understood without a more detailed description, but it is to be understood that numerous changes in the details of construction and in the combination and arrangement of parts may be resorted to without departing from the scope of the invention as hereinafter claimed.

Having thus described my invention, what I claim as new is:—

1. A hat holder including a fixed member, a fulcrum member mounted thereon, spring means disposed between the members so as to hold the lower end of the fulcrum member in engagement normally with the fixed member, and an overhanging extension with a notched terminal provided on the top of the fixed member so as to overhang the upper end of the fulcrum member for the purpose of preventing objects from contacting therewith and the notch allowing ready access to the fulcrum member for operation thereof.

2. A hat holder of the class described including a fixed member provided with an overhanging upper end having a notched terminal and pierced ears disposed intermediate its ends, a movable member having pierced ears intermediate its ends, a pin passing through said pierced ears, a spring

on said pin including a finger at each end thereof, one of said fingers bearing against the fixed member and the other bearing against the movable member so as to normally hold the lower end of said movable member in engagement with said fixed member, the upper end of said movable member being disposed within the overhanging upper end of the fixed member so as to be

protected thereby and ready access being allowed thereto by the notch.

In testimony whereof I affix my signature in presence of two witnesses.

SAMUEL F. PRIEM.
